UNITED STATES PATENT OFFICE

WILLIAM H. ROBERTSON, OF DAYTON, OHIO, ASSIGNOR TO THE NATIONAL CASH REGISTER COMPANY, OF DAYTON, OHIO, A CORPORATION OF MARYLAND

CASH REGISTER

Application filed August 31, 1928. Serial No. 303,249.

This invention relates to cash registers and like machines, and more particularly to improvements in indicating mechanisms for such machines.

5 The invention is applied to a machine of the type illustrated and described in applications for Letters Patent of the United States, Serial Nos. 106,454; 169,583 and 172,660, filed May 3, 1926, February 19, 1927, 10 and March 4, 1927, respectively, by William H. Robertson.

In the practical manufacture and sale of commercially operable machines, profits depend in great measure on quantity production, which in turn necessitates the setting of standards of measurement according to which the machine is manufactured. Deviation from the standards set increases the cost of production of the machine. Nevertheless it oft times becomes advisable, after a machine has been designed and marketed, to include added features not originally provided for, and the problem facing the inventor is to design the added feature or features in such manner that they can be fitted within the limits of measurement heretofore set.

The machine to which the present invention is applied was originally designed with 30 a single set of roller indicators, one indicator roller for each denomination of keys, which indicators were visible from one side of the machine only.

It being found desirable to display the 35 amount of each entry in proper order from both front and back of the machine, a second set of indicator rollers were arranged in alignment with the first set, the corresponding denominational indicator rollers being connected in a manner well known in the art by concentric or nested tubes.

The machines disclosed in these applications are comparatively small but of high capacity, and to provide each bank of 45 numeral keys in the machine with an indicator of a size to be legible at a reasonable distance from the machine, it was found necessary to occupy practically the entire space in the upper part of the machine allotted to the indicating mechanism between the main

frames of the machine. This axial arrangement of indicators occupied so much space, however, that it was necessary to materially reduce the capacity of the machine, that is, to reduce the number of denominational groups or numeral keys to avoid widening the space between the side frames of the machine, which would have been costly in the extreme, since the machine was already in production.

60 Reduction in capacity, however, had its objectionable features, as many lines of business required the indication and registration of larger amounts than could be handled on machines of such comparatively low denominational indication.

It therefore became one object of the present invention to provide the machines of U. S. applications, Serial Nos. 106,454 and 169,583, above referred to having full keyboard capacity, with a simple and novel indicator mechanism which would fit within the confines of such machines, and yet display the amounts set up from both front and back of the machine.

With this and incidental objects in view, the invention includes certain novel features of construction and combinations of parts, the essential elements of which are set forth in appended claims and a preferred form or embodiment of which is hereinafter described with reference to the drawings which accompany and form a part of this specification.

75 In the drawings:

Fig. 1 is a sectional view through the machine taken approximately on line 1—1 (Fig. 4), just to the right of and showing in right elevation, the tens of dollars bank of amount keys together with its differential mechanism and indicator setting and aligning mechanism.

80 Fig. 2 is a detail view of the differential driving mechanism.

Fig. 3 is a detail perspective view of one of the indicators, showing in particular, the flexible connection between said indicator and its setting means.

85 Fig. 4 is a semi-diagrammatic view of the indicator mechanism in which the lateral

distances are maintained, but distorted from front to rear to illustrate the system of transposition used in the indicator setting mechanism.

5 Fig. 5 is a detail view, partly in section, showing the flexible indicator drive and the manner of mounting the indicator and its drive pinion.

10 Figs. 6, 7 and 8 are detail views of the setting mechanism for the front and rear indicators for the units of cents, units of dollars and the thousand dollar denominations, respectively.

15 Before entering into a description of the invention, it is thought best to describe briefly the key controlled differential mechanism incorporated in the type of machine to which the invention is applied. This differential mechanism is fully illustrated and described in applicant's copending applications 20 enumerated above, and to which reference may be had for a full and complete understanding of the machine of which this invention is an improvement.

25 Several banks of amount keys 30 (Fig. 1) are provided, the keys of each bank being slidably mounted in a frame 31 supported on cross rods 34 and 35 extending between the main side frames of the machine, one only of 30 which (32) is shown. The amount to be registered and indicated is set up on the keyboard by depressing the corresponding keys. Means (not shown) retains the keys 30, when depressed, in such positions, and upon the release of the depressed keys 30, springs 36 restore them to their normal undepressed positions.

35 The keys 30, when depressed, interpose their inner ends in the paths of differentially movable toothed adding segments 37, one for each bank of keys 30, pivoted on a rock shaft 38 journaled in the side frames of the machine. The keys, when depressed, also displace zero stop pawls 41 in the corresponding banks, which pawls normally prevent the advance of the adding segments 37. A restraining and restoring rod 39 carried by arms 40, only one of which is shown, fast on the rock shaft 38, normally restrains the adding segments 37 against the influence of springs 47 which tend to advance the segments. At the proper time in the operation of the machine, cams 48 and 49 (Fig. 2) fast on a drive shaft 50 journaled in the machine 45 side frames, rock a bell crank lever 51 pivoted on a stud 46 projecting laterally from the side frame 32, first in counter-clockwise direction and then in clockwise direction to normal through a constant path of travel. Teeth 52 on one arm of the bell crank lever 51 mesh with teeth 53 on a disk 54 secured to one of the arms 40 to rock said arms and the restraining and restoring rod 39 first clockwise and then counter-clockwise back to home 55 position. As the cams 48 and 49 rock the

restraining and restoring rod 39 in clockwise direction, the adding segments 37 in those denominations wherein keys 30 have been depressed, advance with the restraining and restoring rod 39 under the influence of their respective springs 47, until arrested differentially by the inner ends of the depressed keys 30, or by zero stop pawls 41 in the banks wherein keys 30 have not been depressed. The restraining and restoring rod 39, however, 75 completes its full clockwise stroke.

70 Broad pinions 55, (Fig. 1) pivoted on a rod 56, carried by arms 57, only one of which is shown, fast on a shaft 58 journaled in the machine side frames, mesh with the adding segments 37 and also with companion indicator segments 59 also pivoted on the rock shaft 38, one alongside of each adding segment 37, to normally connect the adding segments 37 with the indicator segments 59. 75 However, at the beginning of the operation of the machine, and just before the adding segments 37 commence their clockwise movement, mechanism (not shown) rocks the connecting pinions 55 out of mesh with the pairs of companion segments 37 and 59 to disconnect said segments, so that when the springs 47 advance the adding segments 37 clockwise under the control of the restraining and restoring rod 39, the indicator segments 59 will temporarily remain in the positions to which they were adjusted on the previous operation. The restraining and restoring rod 39, on its clockwise movement, picks up the differentially positioned indicator segments 59 from the various positions to which they were adjusted on the previous operation and restores them to their home positions (Fig. 1) at the limits of their clockwise travel. After all of the indicator segments 59 have been advanced to their home positions by the restraining and restoring rod 39, and the adding segments 37 have been differentially set under the control of their particular keys 30 depressed in their respective banks, or arrested against advance by their zero stop arms 41, the pinions 55 rock into mesh with their respective pairs of companion segments 37 and 59 to again connect these segments.

105 Now, when the cams 48 and 49 rock the restraining and restoring rod 39 counter-clockwise to its home position, the rod restores the differentially advanced adding segments 37 to their normal positions, and the segments 37, through the pinions 55, will rock the corresponding indicator segments 59 like distances, equal, in steps of movement, to the value of the particular keys 30 depressed. Thus, the indicator segments 59 are differentially positioned according to the value of the keys depressed in the several banks of keys.

115 The denominational indicator segments 59 mesh with their respective gears 66, each of which is secured to the inner end of a par-

ticular tube of a nest of tubes 67 surrounding a shaft 68 supported in the side frames 32. Type wheels (not shown) are driven by gears (also not shown) mounted on the outer ends 5 of the tubes 67 to print the amounts as entered in the machine. The parts remain in the several positions to which they have been adjusted under control of the keys 30 depressed, until the next succeeding operation 10 of the machine when the restraining and restoring rod 39, on its clockwise travel, restores the indicator segments 59 and gears 66 to their respective home positions.

The differential mechanism above described is old in the art and forms a part 15 of the present invention only insofar as it cooperates with the novel indicator setting mechanism now to be described.

The indicating mechanism is almost 20 variably arranged in the upper part of the machine within a dome conveniently formed by the side frames 32 of the machine and the cabinet 65 encasing the machine. Widening 25 the distance between the side frames 32 to accommodate front and rear indicator rollers arranged in axial alignment and corresponding denominational with the full denominational keyboards of the prior machines of this type, was not only highly impractical 30 from manufacturing and financial considerations, but also would have merely substituted another problem to be overcome. Such solution would have left considerable space between the keyboard and the side frames, increasing the size of the machine and making 35 it less compact and less easily handled. And if such space was filled with additional mechanism to increase the keyboard capacity of the former machines, the old problem of indicating in front and back to such increased 40 capacity would be immediately restored.

But an increase in the breadth of the dome from front to back necessitates merely a redesign of the cabinet which is a comparatively simple matter, and enables the roller indicators to be arranged in two rows side by side and parallel with the front and back of the machine, and permits the use of a number of indicators in each row equal to 50 the number of denominational banks of keys in the machine. The broadened dome of the cabinet is apertured as at 63, 64 to render visible the indicators in the front and rear rows or groups, respectively.

55 The indicators 77 et al., composing the front group, are rotatably mounted individually on a shaft 70 extending between and journaled in irregularly shaped brackets 71 and 72 (Fig. 4) secured to the respective side frames 32 of the machine. The indicators 60 90 et al. comprising the back group are similarly mounted on a shaft 73 parallel with the front shaft 70 and also journaled in brackets 71 and 72.

65 It is to be understood that there is a bank

of amount keys 30 and a differential mechanism, as just described, for each set of two (front and back) of the amount indicators (Fig. 4) and a bank of transaction keys and a differential mechanism, such as illustrated 70 in Fig. 1, for the transaction indicators, the first indicator on the right in each group, front and back, (Fig. 4), being the transaction indicators.

Indicator setting mechanism interposed 75 between the indicator segments 59 and the parallel groups of roller indicators in the dome of the cabinet 65, simultaneously sets corresponding indicators in the groups of indicators.

The roller indicators and the indicator setting mechanism therefor, appearing in Fig. 1, are associated with the tens of dollars bank of keys. Before proceeding with a description of the system of transposition 80 illustrated diagrammatically in Fig. 4, a description of the manner of setting the tens of dollars indicators will be given.

The roller indicators are all flexibly driven 85 to relieve strain and shock thereon due to the rapid movement and sudden stopping of the differential mechanism, and since the individual flexible driving mechanism for each of the indicators is identical, a detailed description of one of the roller indicators and 90 its flexible driving means is thought to be sufficient.

The gear 66 (Fig. 1) rotated by the differential mechanism under the control of the tens of dollars amount keys 30, meshes with 100 and rotates a mutilated gear 74 on a shaft 75 journaled in the brackets 71 and 72. The mutilated gear 74 meshes with and rotates a pinion 76 on the front indicator shaft 70 and, through the flexible drive mentioned above, rotates the tens of dollars roller indicator 77 to display the amount set up by the depressed 105 keys 30.

Owing to weight of the indicator bodies 110 and the high speeds at which they are rotated, they acquire considerable momentum and the sudden application of power to the pinions 76, 95 coupled with the sudden arrest of the indicators, places a great deal of wear on the toothed connections, for which reason, 115 means, in the form of flexible drive connections, is provided to take up or cushion the shock of suddenly starting and stopping the indicator bodies, and relieve the toothed members of a part of the jar.

120 Such flexible drive connection includes a hub 78 (Figs. 3 and 5), the flange 79 of which is secured to the web 80 of the roller indicator body 77. The hub 78 is rotatably mounted on the hub 81 of the pinion 76, substantially 125 as illustrated in Fig. 5, the two hubs being telescoped on the supporting shaft. A stud 86 projecting laterally from a disk 87 secured to the side of the pinion 76, extends between the ends of a tensioned spring 88 coiled about 130

the indicator hub 78, and a similar stud 89 parallel with the stud 86 and projecting laterally from the flange 79 on the indicator hub 78, also extends between the ends of the 5 spring 88 to retain it under tension. This arrangement, as is clearly illustrated in Figs. 3 and 5, permits of movement of the roller indicator 77 in either direction relatively to the pinion 76, the spring 88, however, normally restraining the roller indicator 77 in and returning it to a constant position relatively to its pinion 76. When the mechanism is started suddenly from a position of rest, 10 the stud 86 in the driving disk 87 suddenly 15 tensions the spring 88 against the inertia of the indicator 77, which lags slightly at the beginning of the movement. When the pinion 76 is brought to a sudden stop at the time when the roller indicator in its rotation, 20 has brought the selected indicia to the sight opening, the spring 88 absorbs the shock incident to the instant arrest of the speed and momentum of the roller indicator, thereby 25 eliminating undue stress and strain on the indicator 77 and its web 80, and relieves the pinion 76 and mutilated gear 74 of this duty.

Such flexible drive is necessitated by the extreme rapidity with which the roller indicators must get under way in turning from one 20 to another of their adjusted positions, and more particularly in view of the sudden arrest to which the wheels are subjected when at full speed, and accumulated momentum.

Experiment has proven that the sudden 25 starting speed coupled with the violent arrest of the roller indicators upon their arrival in the selected positions will quickly damage the indicator and gearing beyond repair if some such flexible drive connection, 40 as that illustrated, is not provided.

To set up the tens of dollars roller indicator 90 on the rear indicator line 73, the mutilated gear 74 rotates an intermediate gear 91 on a shaft 92 journaled in the brackets 71 and 72. 45 The gear 91, through a double sector-gear 93 mounted to rock on a shaft 94 journaled in the brackets 71 and 72, rotates a pinion 95 on the rear indicator shaft 73, which pinion 95, through a flexible connection like that 50 shown in Figs. 3 and 5, adjusts the rear indicator 90 for the tens of dollars bank of amount keys to correspond with the adjustment of the front indicator. Thus it can be seen that the differential mechanism, through 55 the train of gears just described, and through the flexible drives, simultaneously sets the tens of dollars roller indicators 77 and 90 to display the representative character of the key 30 depressed in the tens of dollars bank 60 of keys.

The other denominational front roller indicators are directly set by mutilated gears similar to the gear 74 associated with the tens of dollars indicator setting mechanism 65 (see Fig. 1). But the mechanisms for set-

ting each of the rear roller indicators are peculiar to the roller indicators of individual denominations, therefore, the setting mechanism for each of these indicators will be separately described.

The mechanism whereby the front roller indicator 96 (Fig. 6), and the rear roller indicator 97 for the units of cents bank of numeral keys are simultaneously set, is illustrated in Figs. 4 and 6. As viewed in Fig. 6, the gear 66 for this denomination drives a mutilated gear 98 on the shaft 73 and the gear 98, in turn, drives a pinion 99, which, through a flexible drive, as described above in connection with the tens of dollars indicator, sets the front units of cents denominational indicator 96. In this case, however, the mutilated gear 98 does not rotate an intermediate gear on the shaft 92, the teeth on such mutilated gear, which would normally mesh with such an intermediate gear, being omitted. The pinion 99 for the indicator 96 is fast on the front indicator shaft 70, which shaft is thereby set in accordance with the indicator 96. A pinion 100, fast on the shaft 70 to the left of the group of front roller indicators, as viewed in Fig. 4, rocks a mutilated gear 101 journaled on the shaft 75 to the extreme left of the series of mutilated gears, said gear 101 being exactly like the mutilated gear 74 (Fig. 1) for the tens of dollars indicator setting mechanism. The mutilated gear 101 meshes with and rotates an intermediate gear 102 journaled on the shaft 92, which intermediate gear rocks a double sector-gear 103 journaled on the shaft 94, and this sector-gear rotates a pinion 104 to set the rear units roller indicator 97. A flexible drive, such as is described above in connection with the tens of dollars indicators, is arranged between the pinion 104 and the rear roller indicator 97.

The setting mechanism for the tens of cents roller indicators is essentially the same as that for the tens of dollars denomination described above, excepting that two intermediate gears 113 and 114, are fast on the shaft 92 to transpose the setting of the gear 66 for this denominational bank of keys to the rear indicator therefor. This mechanism does not appear in the drawing in elevation, and will therefore be described in connection with Fig. 4.

The gear 66 (not shown) for the tens of cents denominational keys 30 drives a mutilated gear 110 (Fig. 4) which latter meshes with a pinion 111 journaled on the indicator shaft 70 to set up the front roller indicator 112, and with a gear 113 fast on the shaft 92. Another gear 114 (Fig. 4) also fast on the shaft 92, rocks a double sector-gear 115 on the shaft 94 and this sector gear rotates a pinion 116 on the rear indicator shaft 73 to set the rear tens of cents roller indicator 117. There is a flexible drive, such as previously

described, between the gear 111 and indicator 112, and also between the gear 116 and indicator 117.

The units of dollars indicator setting gears and segments are shown in Fig. 7. In this case, the denominational gear 66 for this denomination sets the front roller indicator 120 through the mutilated gear 121, a pinion 122 and a flexible drive described above, and 10 also rotates an intermediate gear 123 journaled on the shaft 92, just as described above in connection with the tens of dollars indicator. The intermediate gear 123 meshes with a toothed segment 124 fast on the shaft 94, 15 so that rotation of the gear 123 by the mutilated gear 121 and the gear 66, rotates the toothed segment 124 and the shaft 94, which, through another toothed segment 125 also fast on said shaft, rotates an indicator pinion 126, which latter pinion through a flexible drive, sets up the back roller indicator 127 for the units of dollars denomination.

The means for setting the tens of dollars indicators (see Fig. 1) 77 and 90 is fully described above, for which reason no description thereof is necessary at this time.

The hundreds of dollars indicators are set in a manner practically the same as are the indicators for the tens of dollars denomination. The gear 66 (not shown) for this particular denomination, drives a mutilated gear 131 (Fig. 4) on the shaft 75. This mutilated gear rotates an indicator pinion 132 journaled on the front indicator shaft 70 and operates a flexible drive, previously described, to set the front roller indicator 133 for the hundreds of dollars denomination. The gear 131 also rotates an intermediate gear 134 on the shaft 92, which intermediate gear rocks a double sector-gear 135, which, in turn, rotates a pinion 136 fast on the rear indicator shaft 73 to thereby rotate this shaft, and an indicator pinion 137 also fast on the shaft 73, which pinion 137, by a flexible drive, sets the rear tens of dollars indicator 138.

Figure 8 shows the gearing for setting the indicator for the thousands of dollars denomination. In this figure, the gear 66 for this denominational bank of keys drives a mutilated gear 140. In this case, however, this mutilated gear is fast on the shaft 75 which is correspondingly rocked. The mutilated gear 140 rotates an indicator pinion 141 on the front indicator shaft 70 and operates a flexible drive, previously described to set the front indicator 142 for this denomination. A segment gear 143 fast on the shaft 75 to the right of the mutilated gear 98 for the 60 units of cents denomination, (Fig. 4), rotates an intermediate gear 144 on the shaft 92, which gear 144 meshes with a double sector-gear 145 on the shaft 94. This sector gear rotates an indicator pinion 146 on the rear 65 indicator shaft 73 to set up the rear thousands

of dollars indicator 47 through the flexible drive mechanism described above.

An additional pair of roller indicators, 150 for the front and 151 for the rear, (Fig. 4), is provided to indicate the initial or designating character of the clerk operating the machine under the control of the bank of clerks keys (not shown) which are identical with the keys 30 for setting up the amounts. These designating indicators are set by a gear 66 (not shown), which drives a mutilated gear 152 (Fig. 4), intermediate gear 153, double sector-gear 154, indicator pinions 155 and 156 journaled on the respective front and back indicator shafts, respectively, and flexible drives, all of which are identical with the analogous parts described above in connection with the tens of dollars denominational indicators 96 and 97 (see Figs. 1 and 4).

It will be noted that each group of roller indicator mechanisms includes a roller indicator shaft 70 and 73, and a shaft, 75 and 94, to support the mutilated segments, and corresponding double segments, respectively, and that an intermediate shaft 92 is provided to enable the transmission of power from the mutilated segments to the rear roller indicators.

Also it will be noted that power is transmitted from one to another of each member of the denominational sets of roller indicators, except one, through one or another of the roller indicator shafts 70, 73; mutilated segment supporting shaft 75, double segment supporting shaft 94, or intermediate pinion shaft 92, respectively.

Each of the mutilated gears 74, 152, 110, 121, 131, 140, 98 and 101 has a curvilinear slot 157 therein to accommodate an arresting bar 158 extending between the brackets 71 and 72 and adapted to arrest the mutilated gears 74 et al. and consequently the gears 66, indicator segments 59, and the front roller indicators 74 et al. when the restraining and restoring rod 39 returns the indicator segments to their home positions at the end of the forward stroke.

While this arresting bar 158 common to all the mutilated gears might be relied upon to arrest the rear roller indicators 90 et al. in their home positions also, through the intermediate gears 91 et al. and the double segments 93 et al., it is preferred, because of the slight play in the gearing, to provide a similar arresting bar 149 passing through curvilinear slots 148 in the several toothed segments 154, 145, 124, 93, 135, 115 and 103 for this purpose.

Means is provided to align each of the indicators in any of the positions to which they are adjusted by the differential mechanism through the several trains of gears and segments, and under the control of the several banks of keys, one of which banks is shown

in Fig. 1 of the drawings. The aligning mechanism includes a pair of aligner shafts 160 and 161 (Figs. 1 and 4) located intermediate and just above the front and rear indicators, respectively, each shaft having a plurality of identical aligner fingers 162 fast thereon, which fingers co-operate with the indicator pinions 76, 95, etc. to align the indicators 77, 90, etc. in their several positions.

To operate the aligner shafts 160 and 161 to disengage and then to reengage the aligner fingers 162 with the indicator pinions, a pair of cams 163 and 164, fast on a drive shaft 165 journaled in the side frames 32 rock a bell crank 166 pivoted on a stud 167 projecting laterally from one of the side frames 32, to first lower and then to raise a link 168, one end of which is pivoted to one arm of the bell crank. A laterally projecting stud 169 in the upper end of the link 168 projects into slots formed in the overlapping ends of arms 170 and 171 fast on the aligner shafts 160 and 161 respectively. A slot 177 in the link 168 embraces a tie rod 178, which, in addition to tying the indicator brackets 71 and 72 together, serves to guide the link 168 at its upper end.

When the cams 163 and 164 rock the bell crank 166 clockwise, the link 168 rocks the arm 170 and shaft 160 clockwise to disengage the aligner fingers 162 from the front indicator pinions, and at the same time rocks the arm 171 and shaft 161 counter-clockwise to disengage the aligner fingers 162 from the rear indicator pinions. After the indicators have been set by their respective differential mechanisms under control of the depressed keys 30 in their respective banks, the cams 163 and 164 rock the bell crank 166 to raise the link 168 and rock the shafts 160 and 161 in reverse directions to reengage the aligner fingers 162 with their respective indicator pinions, thereby aligning the indicators in their respective adjusted positions.

The machine may be operated either manually by a crank (not shown) or by an electric motor (also not shown) of any suitable design. When the machine is motor driven, the motor rotates a gear 180 on a stud 181 in the side frame 32 through a clutch mechanism (not shown) of conventional design. The gear 180 meshes with gears 182 and 183 fast on shafts 50 and 165, respectively, to turn these shafts one complete rotation in counter-clockwise direction at each operation of the machine.

While the form of mechanism herein shown and described is admirably adapted to fulfill the objects primarily stated, it is to be understood that it is not intended to confine the invention to the one form or embodiment herein disclosed, for it is susceptible of embodiment in various forms all coming within the scope of the claims which follow.

What is claimed as new, is:—

1. In a machine of the class described, the combination with a plurality of indicator-supporting shafts; of a set of indicators mounted on each shaft; an auxiliary shaft associated with each indicator-supporting shaft; a set of gear members mounted on each auxiliary shaft to drive their respective indicators on the indicator-supporting shafts; means to differentially position one set of gear members; and means to transmit motion from the set of differentially positioned gear members to the remaining gear members. 70 75

2. In a machine of the class described, the combination with a plurality of indicator-supporting shafts; of a set of indicators mounted on each shaft; one indicator in each set being fast on its respective shaft; an auxiliary shaft for each indicator-supporting shaft; separate gear members mounted on each auxiliary shaft to drive their respective indicators on the corresponding indicator-supporting shafts; one gear member on each auxiliary shaft being fast to its shaft; means to differentially position the gear members 80 85 on one of the auxiliary shafts; and means intermediate the auxiliary shafts for transmitting motion from the differentially positioned set of gear members to another set of gear members. 90 95

3. In a machine of the class described, the combination with a plurality of indicator-supporting shafts; of a set of indicators mounted on each shaft; one indicator in each set being fast on its respective shaft; an auxiliary shaft for each indicator-supporting shaft; separate gear members mounted on each auxiliary shaft to drive their respective indicators on the corresponding indicator-supporting shaft; one gear member on each auxiliary shaft being fast to its shaft; means to differentially position the gear members on one of the auxiliary shafts; an intermediate shaft; and pinions mounted on the intermediate shaft and meshing with the gear members of the auxiliary shafts to transmit motion from the differentially positioned set of gear members to the remaining gear members, a plurality of pinions being fast on the intermediate shaft. 100 105 110 115

4. In a machine of the class described, the combination of a pair of indicator-supporting shafts arranged in parallel and in substantially the same horizontal plane; a set of roller indicators mounted on each indicator-supporting shaft; one roller indicator of each set being fast to its respective indicator-supporting shaft; an auxiliary shaft parallel and associated with each indicator-supporting shaft; a set of mutilated gears mounted on one of the auxiliary shafts to drive the roller indicators on the associated indicator-supporting shaft; one of the mutilated gears other than that corresponding with the roller indicator which is fast to its supporting shaft, being 120 125 130

- itself fast to its auxiliary shaft; means to differentially position the mutilated gears; a set of segments mounted on the other of said auxiliary shafts to drive the roller indicators 5 on the associated indicator-supporting shaft; one of the segments other than that corresponding with the roller indicator which is fast on the associated shaft, being itself fast on the auxiliary shaft; an intermediate shaft; 10 and a set of pinions mounted thereon and in mesh with the sets of mutilated gears and segments respectively, two of said pinions other than those corresponding with the roller indicators which are fast on their respective 15 indicator-supporting shafts, being themselves fast on the intermediate shaft.
5. In a machine of the class described, the combination with a plurality of indicator-supporting shafts; a set of indicators mounted 20 on each indicator-supporting shaft; an auxiliary shaft associated with each indicator-supporting shaft; an intermediate shaft; a set of differentially adjustable members; and trains of gearing mounted on the auxiliary 25 shafts and the intermediate shaft, certain of which operate to turn the auxiliary shafts, the indicator-supporting shafts and the intermediate shaft, to transmit motion from the differentially adjusted members to 30 the respective sets of indicators.
6. In a machine of the class described, the combination with a plurality of sets of rotatable indicators; a pinion associated with each indicator; and means to variously position the 35 individual indicators; of means to detain the roller indicators where adjusted, comprising a set of detents for each set of indicators, a rotatable shaft for each set of detents, the shafts adapted to rock their respective sets of 40 detents into and out of engagement with the pinions of their associated indicators; arms projecting from each detent shaft towards the other and overlapping at their free ends; the overlapping ends of the arms having reg- 45 istering slots formed therein; a link; means to reciprocate the link; a stud carried by the link and passing through the registering slots to rock the sets of detents simultaneously into 50 and out of engagement with their respective pinions.
7. In a machine of the class described, the combination with a suitable support; of a rotatable indicator comprising an indicator body having a hub journaled on the support, 55 said indicator being rotatable in two directions; a disk having a hub arranged concentric with the hub of the indicator body; a flexible connection between the disk and the indicator body constructed to flexibly drive 60 the indicator in either direction; and means to drive the disk.
8. In a machine of the class described, the combination with a suitable support; of a rotatable indicator comprising an indicator body having a hub journaled on the support, 65 said indicator being rotatable in two directions; a disk having a hub arranged concentric with the hub of the indicator body; the hubs being telescoped; a resilient connection between the disk and the indicator body 70 constructed to resiliently drive the indicator in either direction; and means to drive the disk.
9. In a machine of the class described, the combination with a suitable support; of a rotatable indicator comprising an indicator body having a hub journaled on the support; a disk having a hub arranged concentric with the hub of the indicator body; a spring encircling the hubs; pins projecting towards 75 each other from the indicator body and from the disk, respectively, the respective ends of the spring embracing the pins between them; and means to drive the disk.
10. In a machine of the class described, the combination with an indicator body rotatable in different directions; and a suitable support therefor; of a flanged hub for the indicator body; a driving disk having a hub upon which the flanged hub rotates; means 80 on the flanged hub and on the driving disk projecting laterally from each and toward the other; a resilient device cooperating with said means to rotate the indicator body in either direction upon operation of the driving disk; 85 and means to operate said disk.
11. In a machine of the class described, the combination with an indicator body rotatable in different directions; and a suitable support therefor; of a flanged hub for the indicator body; a driving disk having a hub upon which the flanged hub rotates; a resilient device positioned between said flanged hub and the driving disk; and means connected to the flanged hub and to the driving disk to cooperate with said resilient device 90 to drive the indicator body in either direction. 95
12. In a machine of the class described, the combination with a plurality of indicator supports; of a set of indicators on each support; auxiliary means associated with each indicator support, each auxiliary means carrying a set of devices to drive their respective indicators; means associated with 100 one set of devices to differentially position the same; and means to transmit motion from the differentially positioned set of devices to the remaining set of devices. 105
13. In a machine of the class described, the combination with a plurality of indicator supports; of a set of indicators mounted on each support, certain indicators of each group but of different denominational orders being secured to its respective support; an auxiliary indicator-actuator support associated with each set of indicators; a set of denominational indicator-actuators mounted on each auxiliary support, certain of the actuators of different denominational orders being 110 115 120 125 130

- cured to said auxiliary supports, said certain actuators being of different denominational orders than the above-mentioned certain indicators; means to differentially position one set of indicator-actuators to drive its associated set of indicators differentially; and a third support carrying a plurality of denominational means to connect the sets of denominational indicator-actuators, certain 5 of said denominational connecting means being secured to the last mentioned support, said certain denominational means being of different denominations than said certain denominational actuators and said certain 10 denominational indicators, all of the denominational actuator-connecting means acting to transmit motion from the differentially driven set of indicator actuators to another set of indicator actuators.
- 15 20 14. In a machine of the class described, the combination of a plurality of indicator supports; of a set of indicators mounted on each support, said indicators being arranged in pairs, one indicator of each set and of unlike pairs being secured to its respective support; 25 means including sets of indicator actuators to transmit movements of like extent from one set of indicators and from one support to the other set of indicators and to the other 30 support to drive the indicators of each pair to the same extent; and means to differentially position one set of indicator actuators to determine the extents to which the pairs of indicators are to be driven.
- 35 35 In testimony whereof I affix my signature.
WILLIAM H. ROBERTSON.
